UNITED STATES PATENT OFFICE.

HENRY C. KARR, OF WASHINGTON, DISTRICT OF COLUMBIA, ASSIGNOR OF ONE-FIFTH
TO EMIL BONNELYCKE, OF WASHINGTON, DISTRICT OF COLUMBIA.

SHIPPING PACKAGE FOR WATCHES.

1,423,329.

Specification of Letters Patent.

Patented July 18, 1922.

Original application filed February 18, 1921, Serial No. 446,067. Divided and this application filed May 26, 1921. Serial No. 472,815.

To all whom it may concern:

Be it known that I, HENRY C. KARR, a citizen of the United States of America, residing at Washington, District of Columbia, have invented certain new and useful Improvements in Shipping Packages for Watches, of which the following is a specification.

In my prior application, Serial No. 10 446,067, filed February 18, 1921, there is disclosed and claimed a watch stand or holder which is applicable to, and capable of use with, watches of widely different styles and sizes, and which is so constructed that a 15 watch may be easily and quickly engaged and disengaged with and from the holder and, when placed therein, will be supported in reading position.

The present application, which is a division 20 of the above-identified application, relates to the provision and arrangement of the holder and the box or case therefor; the essential object of the invention being the production of an improved package consisting 25 of the case or box, the holder and the watch, and in which the holder functions as a guard for the watch or more specifically as a spring cushion, so that the package may be shipped through the mail in comparative 30 safety.

For this purpose, the present invention provides a watch stand or holder constructed from a suitable blank of resilient material which is bent into the form of an 35 inverted yoke. The major portions, or legs of the yoke, converge upwardly when the holder is in position to support a watch, and are spaced at their upper ends by a connecting portion or bridge, the latter portion 40 having a part which is adapted to engage the stem of the watch.

Now according to this invention, when 45 making up the package the watch is inserted edgewise in the holder with its stem engaged in the part provided therefor in the bridge portion, so that the body of the watch is thus disposed in the space between the legs of the holder which extend across the opposite sides or faces of the watch. When so 50 arranged, the watch and holder are laid flat in the box, the legs of the holder serving as spring cushions or guards which will take up and absorb any light shocks to which the box may be subjected.

In the accompanying drawing: 55
Figure 1 is a perspective view of the improved holder, and

Figs. 2 and 3 are, respectively, a part sectional plan view and a longitudinal vertical section illustrating the conversion of the holder into a shock absorbing or cushioning device to protect the watch against injury during shipment, showing the case or box in which the holder and the watch are packed. 60

Referring more particularly to the drawing, the stand or holder, as described in detail in my aforementioned prior application, is constructed from a single strip or blank which may be of sheet material, either metal or non-metal as may be preferred; and it comprises an upwardly extending, substantially upright body portion and a supporting base at the foot thereof. 65

As represented in Fig. 1, the holder preferably takes the form of an upright or inverted yoke, the legs 1 of which converge toward each other and are connected at their upper ends by a bridge-piece 2. The latter, when the stand is in upright or normal position, extends horizontally in a forward direction and has the appearance of a loop or U, the bight of which is at the front thereof, said bridge being designed to normally engage the top part of the body 4 of the watch 5 and to straddle the stem 6 70 of the watch. The ability of the bridge to so engage or straddle the watch stem is dependent, of course, upon the U-shaped formation of the bridge, the open central space 80 of which virtually forms a slot. 75

The base of the stand or holder is formed by the enlarged lower ends 3 of the legs, which ends extend both forwardly and rearwardly from the legs and constitute elongated supporting feet. The front portions of 85 these feet are utilized to support the lower portion of the watch and, conjointly with the bridge 2, to maintain the watch in proper upright reading position in the holder. To this end, the aforesaid front 90 portions are constructed to provide or produce pockets, indicated at 7, wherein the lower portion of the watch is received, these pockets being located immediately at the foot of the legs 1 so that the rear edges of 100 the pockets are, in fact, constituted by continuations of the front edges of said legs, the pockets being curved or concave and of 105

sufficient width to enable the bottom of the watch body to conformably fit therein.

The form of holder above described readily lends itself for use as a shock absorbing or cushioning device for the watch when the latter is to be shipped by mail or otherwise. When so used, the watch is detached from the holder and then re-inserted sideways between the legs 1, so that one leg will 10 overlie and the other leg will underlie the watch in the manner indicated in Figs. 2 and 3. The holder, with the watch so placed therein, can then be inserted in the box or case 10, which may be of the type ordinarily 15 used for display purposes, or may be of the type comprising a sliding cover; the size of the box being such that the watch will have a more or less close fit therein. When so positioned, the two legs of the holder will 20 engage the top and bottom of the box and constitute yielding cushions which will absorb and deaden any ordinary shocks or vibrations which may be imposed upon the box while in transit. The box, the watch 25 and the holder thus conjointly form an improved shipping package which may be readily carried about and transmitted by parcel post or the like in comparative safety.

I claim as my invention:—

30 1. An improved shipping package for watches, comprising a box; a spring yoke

laid flatwise therein and embodying a pair of spaced legs and a bridge connecting the same; and a watch inserted sidewise between said legs and having its stem engaged with 35 said bridge, so that one leg overlies and the other leg underlies the watch to cushion the latter against shocks imparted to the box.

2. An improved shipping package for watches, comprising a box; a spring yoke 40 laid flatwise in the box and embodying a pair of spaced legs and a bridge therebetween formed with a slot; and a watch inserted sidewise between said legs and having its stem engaged in said slot, one leg 45 overlying and the other leg underlying the watch so as to cushion the latter against shocks imparted to the box.

3. An improved shipping package for watches, comprising a box; a combined 50 watch stand and shock absorbing element fitting in the box and embodying spaced cushioning portions arranged one above the other; and a watch inserted sidewise between said cushioning portions so that one 55 overlies and the other underlies the watch, said element adapted to support the watch in normal reading position when removed from the box.

In testimony whereof I affix my signature. 60

HENRY C. KARR
